Specification for Design.

Patented Mar. 11, 1919.

Application filed September 25, 1917. Serial No. 193,202. Term of patent 14 years.

To all whom it may concern:

Be it known that I, FRANK J. TONE, a citizen of the United States, residing at Niagara Falls, in the county of Niagara and State of New York, have invented a new, original, and ornamental Design for Cans, of which the following is a specification, reference being had to the accompanying

drawing, forming part hereof, in which the figure is a perspective view of a can embodying my invention.

I claim:

The ornamental design for a can, as shown. In testimony whereof I have hereunto set my hand.

FRANK J. TONE.
